[57] ABSTRACT

A method and apparatus for congealing liquids wherein a refrigerating fluid carries heat away from one side of a heat-conducting wall and a congealed layer is formed on the other side of the wall. The amount of refrigerating liquid supplied to the wall surface is reduced when the congealed layer builds up sufficiently to produce a major heat transfer bottleneck. The apparatus has a freezing cylinder drum which rotates in a body of water with its top portion above the water surface where an internal roller deflects the cylindrical drum and peels the ice free. The ice contains a low concentration of boron which is substantially identical with the concentration of boron in the water.

FIG.1

FIG.2

FIG.3

ICE MAKING MACHINE AND METHOD

This invention relates to congealing liquids and more in particular to freezing water solutions in an improved and dependable manner.

An object of this invention is to provide machines and methods for congealing liquids which are more efficient and economical than those previously available. A further object is to provide for congealing liquids in a manner which is not handicapped from the standpoint of economy and performance because of high heat barrier characteristics of the congealed product. In the past, ice and other congealed products have been produced by utilizing secondary refrigerant liquids such as brine and glycol-water solutions. The refrigerant liquid is cooled in an evaporator-chiller of a refrigeration system and is then pumped through a congealing machine or unit having a flexible wall of high heat-conductivity with a freezing surface on one side upon which a layer of the congealed product is formed, and the refrigerant liquid flows along the other side of the wall and carries away the heat extracted from the liquid being congealed. The present invention constitutes an important improvement in such congealing methods and apparatus.

In the illustrative embodiment of the present invention, an ice making or congealing machine is used which is of the type disclosed in my prior U.S. Pat. No. 2,257,904. The liquid to be congealed is a water solution containing a predetermined concentration of boron, and the ice which is formed contains boron in the same or an insignificantly different concentration. In the illustrative embodiment, the congealed product is utilized as a safety mechanism in the event of an explosion of a nuclear reactor in a power plant, the ice being available to act as a "radiation and heat sink" to absorb instantaneously large quantities of radiation and heat with a minimum rise in temperature and pressure. However, it is understood that the invention has other uses, for example, in processing various food and chemical products.

In the drawings:

FIG. 1 is a schematic representation of one embodiment of the invention;

FIG. 2 is a plan view showing the distribution of jet nozzles in the drum sheet of the ice making machine of FIG. 1; and

FIG. 3 is an enlarged fragmentary section on the line 3-3 of FIG. 1.

Referring to FIG. 1 of the drawings, an ice-making machine 2 is of the general type shown in my U.S. Pat. No. 2,257,904. Machine 2 has a flexible cylinder 4 immersed other than at its top in a body 6 of a water solution in a tank 8. Cylinder 4 has an exterior freezing surface 52, and is mounted at its ends by a structure (not shown) including end plates and stub shafts upon which it rotates about its axis 10. Within the cylinder there is a stationary structure 14 which includes a deflecting roller 12 at the top and a cylindrical drum sheet 16 which is substantially coaxial with the cylinder. The drum sheet is of slightly less radius than the cylinder so that (see also FIG. 3) it is parallel to and spaced from the inner surface 50 of the cylinder. The drum sheet is perforated in accordance with a pattern to be discussed below so as to provide holes in each of which there is mounted a nozzle 18 from which a jet of cold brine is impinged against the inner surface of cylinder 4. The cold brine is recirculated to and from the cylinder in

the manner disclosed in the above-identified patent, first it is pumped under pressure axially into the central space 17 surrounded by the drum sheet and it then flows with the jet action through the nozzles into the toroidal space 19 (FIG. 3) between the drum sheet and the cylinder. The brine then flows upwardly between the rows of jets to a top horizontal discharge passage-way 21 from which it is withdrawn through an axial discharge conduit (not shown). The pressure difference between space 17 and 19 insures a strong jet action projecting the brine jets through the body of brine against the internal surface 50 of the cylinder wall. As will be explained below, the jets of brine circulate the surrounding body of brine and also break up the liquid film on surface 50 so as to provide a high coefficient of heat transfer from the cylinder wall to the brine.

As shown schematically, the brine is cooled by passing it to and from an evaporator-chiller 20 which is part of a refrigeration system, which also includes a compressor 22, a condenser 24, a receiver 26, an expansion valve 28 and other standard components not shown.

As an area of cylinder 4 rotates clockwise from the two o'clock position 30, its freezing surface 52 moves downwardly into the water solution and a layer of ice starts to form on the freezing surface. The thickness increases to approximately the 10 o'clock position 32 where the freezing surface emerges from the water solution, and the ice is then sub-cooled as it moves on to the zone of deflecting roller 12. When passing over the deflecting roller, the cylinder is deflected sufficiently to cause the ice to peel away from the freezing surfaces in the form of a free ribbon of ice 34. Illustratively, the ice passes to a bin 36.

FIG. 2 shows the positioning of nozzles 18 on the drum sheet. Extending longitudinally of the drum sheet between the edges 40 and 42 are nine parallel active perimeter areas 43, each of which is separated from the next by an inactive perimeter area 40'. In slightly more than one-half of each active perimeter area adjacent to the top edge 40, there is one nozzle per square inch of the active perimeter area, whereas in the bottom portion which extends toward edge 42 there is one nozzle for each two square inches of the active perimeter area.

When the drum sheet 16 is installed (FIG. 1) in cylinder 4, edge 40 is at the one o'clock position 30, and edge 42 is at the 11:30 o'clock position. Hence, the jets of cold brine from each of the active perimeter areas 43 forms a perimeter freezing zone on the freezing surface 52 of the cylinder. Each of the freezing zones has an area extending approximately 180° clockwise from position 30 which is subjected to the cooling effect of the cold brine from the larger number of the jets which are positioned one per square inch, whereas the remainder of the freezing zone is subjected to the cooling effect of brine from the smaller number of jets which are spaced one per two square inches.

Referring now to FIG. 3, there is represented somewhat schematically, a section of cylinder 4 along a radial plane at position 32, where a layer of ice 34 is adhered to the freezing surface 52. In the initial stage of the formation of layer 34 a portion of the cylinder moves downwardly below the surface of the water solution and a small film of ice immediately forms on surface 52. In this embodiment, the body 6 of the water solution is at a temperature which may be substantially above its freezing temperature of 31.5°F, and the cold brine at -10°F is projected through nozzles 18 in the

form of the jets represented by arrows 54. The spacing of the jets and the rate of delivery of brine is such that surface 50 is maintained at substantially the temperature of the brine. Hence, at position 30 there is a temperature gradient of more than 41.5°F between the water solution at surface 52 and the brine at surface 50. However, the film of ice which forms immediately on surface 52 is a very excellent heat insulator, whereas cylinder 42 is a very excellent heat conductor. Therefore, the layer of ice soon becomes a much greater heat-transfer barrier than the cylinder wall.

The jets of brine have sufficient force to break up the liquid film on surface 50 and the quantity of brine is sufficient to carry away the heat which passes to the cylinder wall through the layer of ice. Hence, the layer of ice builds up and the cylinder wall approaches the temperature of the brine. Therefore, the present invention takes into account, when the layer of ice reaches its maximum thickness, substantially the entire temperature gradient is between surface 56 and 52, and the temperature gradient between the surfaces of the cylinder wall is negligible. The present invention takes into account the fact that the layer of ice is then the heat-transfer "bottleneck." That is, the rate of heat transfer from surface 56 to the brine is limited by the rate at which the heat will pass through the layer of ice at the existing temperature gradient. However, the amount of brine circulated is always sufficient to maintain a substantially 0°F temperature gradient across the cylinder wall and substantially the entire temperature gradient between the brine and the ice surface 56 is maintained across the layer of the ice. That produces the maximum heat transfer to the brine and therefore the maximum congealing rate for the brine and water temperatures.

In accordance with the present invention, no more brine is circulated than is necessary to carry away the maximum amount of heat which will pass through the layer of ice as its thickness increases. The circulation of brine at a rate in excess of that amount would not increase the rate of heat transfer from the ice surface and therefore would not increase the congealing rate. The reduction in the amount of brine projected against the cylinder wall surface 50 when the ice layer builds up to a pre-determined value, does not reduce the temperature gradient across the surfaces of the layer of ice, and the rate of heat transfer therethrough is maintained at the maximum value. As indicated above, the reduction in the rate of circulation of brine is effected by reducing the number of nozzles from one per square inch to one per two square inches of the active perimeter areas. However, the layer of ice is still the heat-transfer bottleneck and there is still sufficient brine circulation to maintain the entire cylinder wall in the freezing zones at substantially the temperature of the brine.

The reduction in the rate of circulation in the brine materially improves the overall efficiency of the system and makes it possible to maintain satisfactory operating conditions. The circulation of unnecessary brine would produce an objectionable heat load, and any reduction in such circulation is beneficial to the system. For the particular ice-making installation herein disclosed, only one-half the amount of brine is circulated for approximately one-half of each of freezing zones. That permits a reduction of the order of 25 percent in the sizes of the brine handling and chilling components, i.e., pumps, lines and chiller. Also, as indicated, it reduces the overall size of the refrigeration system. Hence, there is a

substantial reduction in the initial cost of the installation as well as in the cost of the operation.

An important aspect of the present invention is that nozzles 18 direct discrete jets of brine against surface 50 so as to break down the films on the surface and increase the rate of heat transfer between the cylinder wall and the brine. Illustratively, nozzles 18 have orifices of 0.087 inch diameter, and the spacing between the nozzles and surface 50 is of the order of 0.51 inch. 10 Each of the active perimeter areas 43 is subjected to intensive jet action, whereas the inactive areas 44 provide peripheral paths for the brine to flow upwardly beyond the edges 40 and 42 of the drum sheet and thence axially to the discharge port (not shown). Hence, an efficient flow path is provided with the drum sheet forming an inlet chamber in which the brine is confined under pressure and from which it is discharged as jets impacting against surface, and the brine from each jet then passes to the next adjacent inactive area and along it upwardly to the axial discharge passageway.

The first film of ice is in the form of thin ribbons one directly over each of the jets and having a cross-section in the form of a single base ellipticordial segment with its center directly over the center of its jet. The layer then builds up by the merging of the separate ribbons as the thickness increases. The increase in thickness of the ice being frozen follows the well known exponential law of growth, which may be plotted upon "semilogarithmic" paper. The curve is a straight line when shown in a coordinate graph the abscissae of which are time in equal increments and the ordinates are the corresponding logarithms of the thickness of the ice. Tests show that the slope of the line changes abruptly at the ice thickness where the ice becomes the dominant transfer barrier. Hence, those tests indicate one rate of ice growth until the ice becomes the dominant heat-transfer bottleneck and another rate of ice build up thereafter.

40 In the illustrative embodiment, the refrigerating liquid is 28 percent calcium chloride brine which has relatively low viscosity. Tests have also been conducted with the refrigerant liquid formed by equal parts of water and ethylene glycol, which has relatively high viscosity. However, the jet action effectively breaks up the surface film even with the high viscosity solution.

I claim:

1. In the art of freezing thin layers of ice from a water solution containing dissolved or dispersed other materials, the steps of, covering a freezing surface with the solution throughout a freezing zone, refrigerating said freezing surface through a conducting wall by projecting a chilled liquid at a controlled temperature and at a controlled quantity rate against the opposite surface 55 of said wall to form an initial layer of ice on said freezing surface until the layer of ice is of a sufficient thickness to constitute a substantial heat transfer bottleneck between the solution and the chilled liquid and thereby reduce the heat transfer rate at which heat passes from the solution to the chilled liquid at the temperature gradient between the chilled liquid and the freezing temperature of the solution, and then reducing the quantity rate at which the chilled liquid is projected against said surface to thereby reduce the quantity of chilled liquid projected against a given area of said opposite surface to take into account said reduced rate of heat transfer from the solution.

2. The method as described in claim 1 wherein said water solution is borated water and wherein said ice is borated ice of a thickness of 0.1 inch and contains substantially the same concentration of boron as the borated water.

3. The method as described in claim 1 wherein the initial layer of ice has a thickness of 0.06 inch and the final thickness of the ice is of the order of 0.1 inch.

4. In the art of congealing liquids, the steps of, moving a wall having a congealing surface thereon through a congealing zone within a body of liquid to be congealed to said congealing surface, supplying refrigerant fluid at a determined effective temperature to the side of said wall opposite said congealing surface at a controlled rate throughout an initial portion of said freezing zone to thereby form an initial layer of congealed liquid which produces a decrease in the heat transfer rate at which heat is transferred from the liquid solution to the refrigerant fluid at the temperature gradient between the refrigerant fluid and the congealing temperature of the liquid, and supplying said refrigerant fluid at a reduced rate to said opposite surface throughout the subsequent portion of said freezing zone to thereby reduce the quantity of said refrigerant fluid delivered to a specific area of said opposite surface to correspond to said reduced rate of heat transfer of heat from said liquid.

5. In the art of congealing liquids as described in claim 4 wherein the liquid being congealed is water and the refrigerant fluid is brine, and wherein jets of brine are projected through a body of brine against said wall with sufficient force to displace the liquid film on the wall surface.

6. In the art of congealing liquids as described in claim 5 wherein said wall is substantially cylindrical and flexible, the step of, rotating said wall substantially about its axis.

7. In apparatus for congealing liquid, a substantially cylindrical metal wall having an exterior freezing surface and an internal refrigerated surface, means immersing said cylindrical metal wall in a body of liquid

except at its top portion, means for rotating said wall, nozzle means positioned along the part of and directed toward said refrigerated surface, supply means to project jets of refrigerated liquid from said nozzle means against said refrigerated surface substantially throughout the path of its movement while being immersed, said nozzle means and said supply means being constructed to deliver a predetermined quantity of said refrigerated liquid at a predetermined effective temperature against a specific area of said refrigerated surface throughout its movement along the initial portion of its path immediately after being immersed to thereby form an initial layer of congealed liquid on said freezing surface which reduces the heat transfer rate at which heat passes from said body of liquid to said refrigerated liquid at the temperature gradient therebetween and supplying said refrigerated liquid at a reduced rate in a subsequent portion to thereby reduce the quantity of refrigerated liquid delivered to said specific area of the refrigerated surface in accordance with said reduction in the heat transfer rate of heat from the body of liquid.

8. An apparatus as described in claim 7 wherein said nozzle means comprises a nozzle plate and a plurality of nozzles mounted thereon in spaced relationship, said nozzles being spaced further from each other in said subsequent portion than in said initial portion to provide said reduced rate of liquid delivery.

9. Apparatus as described in claim 8 wherein the space between said nozzle plate and said cylindrical wall is occupied by a body of liquid and said nozzle plate provides an inlet chamber for said refrigerated liquid, and means to chill said refrigerated liquid and deliver it to said inlet chamber at a pressure sufficient to cause it to flow through said nozzles and displace the liquid film on the adjacent wall surface.

10. Apparatus as described in claim 7 which includes a refrigeration system with an evaporator-chiller through which said refrigerated liquid is circulated to said nozzle means.
